(57) CLAIM

The ornamental design for a combination golf putter stand and practice target, as shown and described.

DESCRIPTION

FIG. 1 is an environmental perspective view of a first embodiment of a combination golf putter stand and practice target illustrating my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a bottom plan view thereof; and,

FIG. 7 is a top plan view thereof.

The broken line showing of environmental structure in FIG. 1 is for illustrative purposes only and forms no part of the claimed design.
